UNITED STATES PATENT OFFICE.

GEORGE W. ROTHENBERGER AND WILLIAM HAYDEN, OF READING, PENNSYLVANIA.

ADJUSTABLE GARMENT-PATTERN.

1,175,996.

Specification of Letters Patent. Patented Mar. 21, 1916.

Application filed May 29, 1915. Serial No. 21,095.

To all whom it may concern:

Be it known that we, GEORGE W. ROTHENBERGER and WILLIAM HAYDEN, both citizens of the United States, residing at Reading, 5 in the county of Berks and State of Pennsylvania, have invented certain new and useful Improvements in Adjustable Garment-Patterns, of which the following is a specification.

10 Our invention relates to adjustable garments patterns of the type shown in Patent No. 1,049,536, issued to us January 7th, 1913, and our present improvements relate to patterns for forming the tubular portions of a 15 suit, to wit, the trousers and sleeves.

The invention is fully described in connection with the accompanying drawings and the novel features are specifically pointed out in the subjoined claims.

20 Figure 1 is a plan view of a back portion and Fig. 2, a plan view of the front portion of a pattern for a pair of trousers; the outline of the several adjusted sections being slightly varied from the true blending lines 25 as shown so as to more clearly distinguish the outlines of the separate connected sections. Figs. 3 and 4 are similar plan views of the upper and under side of a sleeve pattern embodying certain features of our invention.

As shown our invention consists of a main section, either in a single piece or of two connected pieces, to which is adjustably secured an extension section or sections to vary the 35 length of the pattern, one or more edges of the main and extension sections having a number of outline sections adjustably connected to each other and to the main and extension sections so as to permit varying the 40 outline of the pattern to suit individual measurements and adapt the pattern for cutting a variety of styles and sizes of garments.

In Figs. 1 and 2 is shown a pattern embodying our invention and adapted for cutting the rear and front portions of a pair of trousers. In this case the main section is formed of two pieces of sheet material 5, 6 and 5^a, 6^a respectively for the front and rear 50 pattern roughly conforming to the general shape of the pattern desired and with their meeting edges overlapping and pivotally connected at their upper ends at 7 and 7^a respectively, by means of suitable set screw devices. Their lower ends are connected by a similar set screw device engaged in a slot,

8 and 8^a respectively; so that the pieces may be swung on their pivotal connections, 7 and 7^a, to vary the spread of the lower end of the main sections for a purpose hereinafter described.

To the main section of each front and rear pattern is secured a bottom extension, 10 10^a respectively, of a single sheet of material as shown, roughly conforming to the general 65 outline of the pattern, and adjustably connected to the main section by screw devices 11 and 12, and 11^a and 12^a respectively, engaged in converging slots 13 and 14, and 13^a and 14^a formed in the respective extension 70 sections 10 and 10^a.

The upper extension of the main section of each pattern is formed, as shown, of two overlapping sheets 15 and 16 and 15^a, 16^a respectively, pivotally connected at 17 and 17^a along their upper edges, and respectively connected to their main sections by screw devices 18 and 19 and 18^a and 19^a engaged in converging slots 20 and 21 and 20^a and 21^a respectively formed in the extension sections 80 15 and 16 and 15^a and 16^a.

The inner seam edge of the rear portion of the pattern (Fig. 1) is formed as shown of outline sections of sheet material overlapping the main and extension sections and 85 comprise the parts 30, 31, 32, 33, 34, and 35 as shown. Horizontal slots 36 and 37 in part 10, 38, 39 and 40 in part 5, and 41 in part 15 permit movement of the sections to vary the width of the pattern, while vertical 90 slots 42 in part 30, 43 in part 34, and 44 in part 35 permit adjustment of the sections as required by the vertical adjustments of the extension sections 10 and 15—16 upon the main section 5—6. The sections 31 and 32 95 are pivoted together at 45, and the sections 32 and 33 are pivoted together at 46. The inner edge of the front pattern is similarly formed and adjustably connected each to the other and to the main and extension sections 100 as shown.

The outer seam edge of the rear pattern is formed as shown of overlapping sections 50, 51, 52, 53 and 57, horizontally adjustable upon the main and extension sections by 105 means of slots 58, 59, 60, 61 and 63 and vertically adjustable upon each other by slots 64 and 65. The outer seam edge of the front pattern is similarly formed, but owing to the greater variation in shape desired to 110 suit different styles and variations in waist shape and sizes, additional sections are pro-

vided as shown with additional vertical and horizontal adjustments on the main and extension sections.

The converging slots 13 and 14, provide for proportionate spread of the lower ends of the main section 5-6 to conform to the vertical adjustment of the extension section 10, spreading also the outline sections connected to the main section, to maintain a desired conformity of curvation, which however may be changed if desired by adjustment of the outline sections. Similarly the converging slots 20 and 21 spread the upper extension sections 15 and 16. The slots 13^a-14^a and 20^a-21^a perform a like function for the front pattern. It is understood of course that two pieces of cloth must be cut from each front and rear pattern to make up a pair of trousers.

Figs. 3 and 4 indicate our pattern built to shape a sleeve, Fig. 3 being the upper and Fig. 4 the under arm patterns. In this case the main section of each pattern, 5^b and 5^c respectively, is formed of a single sheet material section, and a bottom extension section 10^b and 10^c is in each case provided, having slots 13^b-14^b, and 13^c-14^c for vertical adjustment. Variations in the outline are necessary only along the outer seam and for the arm hole, and these are provided by the seam outline sections 50^b-51^b and 50^c-51^c respectively, for each pattern, horizontally adjustable by means of slots 58^b-60^b and 58^c-60^c and vertically adjustably by slot 64^b and 64^c respectively; while the arm hole adjustments are provided for by the sections 70, 71, 72 and 73, as shown, for the upper pattern and by sections 70^c, 73^c, for the under arm pattern.

Scales are provided at the various points of adjustment by which the sections may be set to conform to the measurements of each individual, and the set screw devices permit of readily moving and locking the adjusted parts.

Our patterns permit cutting trousers and sleeves of various sizes and shape from the one pattern, thus avoiding the drafting of a pattern to suit each individual, while the converging slots of the extension sections insure the maintaining of proportionate curvation of the pattern outline in conformity with the adjustment as to length.

What we claim is:

1. A garment pattern comprising two main sections 5 and 6 pivotally connected at one end and adjustably connected at the other end, an extension section 10 at the latter end of the main sections having converging slots 11 and 12, locking pins in said main sections engaged in said converging slots and adapted to swing said sections on their opposite pivotal connection in proper proportion to the vertical adjustment of the extension section, and an outline section ad-

justably connected to said main and extension sections, substantially as shown and described.

2. A garment pattern comprising two main sections 5 and 6 pivotally connected at one end and adjustably connected at the other end, two upper extensions 15 and 16 of said main sections pivotally connected at their upper ends, converging slots 20 and 21 in said extension sections, locking pins in the main sections engaged in said converging slots and adapted to swing said extension sections on their pivotal connections to spread their lower ends in proper proportion to their vertical adjustment, and outline sections adjustably connected to said main and extension sections, substantially as shown and described.

3. A garment pattern comprising two main sections 5 and 6 pivotally connected at one end and adjustably connected at the other end, two upper extensions 15 and 16 of said main sections pivotally connected at their upper ends and having converging slots 20 and 21, a single lower extension 10 of the main sections having converging slots 13 and 14, locking pins in the upper and lower edges of the main sections engaged in the converging slots of the upper and lower extension sections, and adapted to swing said main and upper extension sections on their pivotal connections to spread their lower adjustable ends in proper proportion to the vertical adjustment of said extension sections, and outline sections adjustably connected to said main and extension sections, substantially as shown and described.

4. A garment pattern comprising two main sections 5 and 6 pivotally connected at one end and adjustably connected at the other end, two upper extensions 15 and 16 of said main sections pivotally connected at their upper ends and having converging slots 20 and 21, a single lower extension 10 of the main sections having converging slots 13 and 14, locking pins in the upper and lower edges of the main sections engaged in the converging slots of the upper and lower extension sections, and adapted to swing said main and upper extension sections on their pivotal connections to spread their lower adjustable ends in proper proportion to the vertical adjustment of said extension sections, and outline sections 30, 31, 32, 33, 34 and 35 adjustably connected to said main and extension sections and to each other to form the inner seam edge of the pattern, substantially as shown and described.

5. A garment pattern comprising two main sections 5 and 6 pivotally connected at one end and adjustably connected at the other end, two upper extensions 15 and 16 of said main sections pivotally connected at their upper ends and having converging slots 20 and 21, a single lower extension 10

of the main sections having converging slots 13 and 14, locking pins in the upper and lower edges of the main sections engaged in the converging slots of the upper 5 and lower extension sections, and adapted to swing said main and upper extension sections on their pivotal connections to spread their lower adjustable ends in proper proportion to the vertical adjustment of said 10 extension sections, and outline sections 30,

31, 32, 33, 34 and 35, and 50, 51, 52, 53, and 57, adjustably connected to said main and extension sections and to each other to form respectively the inner and outer seam edges of the pattern, substantially as shown and 15 described.

In testimony whereof we affix our signatures.

GEORGE W. ROTHENBERGER.
WILLIAM HAYDEN.
